CONSOLE FOR FAULT DETECTOR FOR PAPER WEBS

Pentti Kalervo Mannonen, Kuohukuja 6 D 51,
01600 Myyrmaki, Finland

Filed July 2, 1973, Ser. No. 375,878

Term of patent 14 years

Int. Cl. D10—05

U.S. Cl. D10—46

FIG. 1

FIG. 2

FIG. 1 is a left front perspective view of a console for a fault detector for paper webs showing my new design, the right side, top, bottom and rear being substantially plain and unornamented;

FIG. 2 is a left front perspective view thereof with the front door in the open position.

I claim:

The ornamental design for a console for fault detector for paper webs, as shown.
